UNITED STATES PATENT OFFICE

ABRAM-LOUIS JEANNERET, FILS, OF LA CHAUX-DE-FONDS, SWITZERLAND, ASSIGNOR
TO COMPTOIR GENERAL DE VENTE DE LA MONTRE ROSKOFF SOCIETE ANONYME
VVE. CHS. LEON SCHMID & CIE, OF LA CHAUX-DE-FONDS, SWITZERLAND

ELECTRICAL CLOCK

Application filed April 18, 1927, Serial No. 184,802, and in Germany December 10, 1926.

The present invention relates to an electrical clock for which the motive power is furnished by a main spring bent periodically by the oscillating armature of an electro-magnet. The power of said spring is transmitted to the clockwork and this latter closes a circuit actuating said armature or pallet before the said spring is completely unbent. During the short time of the bending of the main spring a small auxiliary spring bearing on the pallet furnishes the impulse for keeping up the movement of the clockwork.

Such an arrangement has the advantage to set in readiness the power required for breaking the circuit when the pallet begins to move so that, when a gradual decrease of the voltage at the source of the current is produced by the consumption of current which will show itself by a decrease of the sway of the armature, the breaking can be effected with the required power furnished by the auxiliary spring.

In the accompanying drawing a working form is shown of the object of the invention.

Figs. 1 and 2 are plan views, Fig. 1 showing the position of parts when the circuit is open and Fig. 2 when it is closed.

30 Armature 5 is pivotally supported between the poles 2 of the electro-magnet 3 by an axle 4 which takes the place of the barrel arbor of the clock. A contact nose 18 provided with a carrier pin 20 and forming one member of a make and break contact device is rigidly fast to the armature and likewise a cross arm 6 which is attached by a tension spring 7 which is the main spring of the clock, to a stationary stud 8.

40 On the same axle 4 is also mounted loose an insulating arm 19 which is coupled trailingly with the contact held loose on the axis 4 and is connected with the contact nose 18 by means of a circularly curved hair spring 25. A contact piece 22 forming the second

member of the make and break contact device is fast to a flat spring 23 bent off at its free end at 26. The insulating arm 19 is provided with two notches 27, 28 separated by a tooth 29 and forming rests for the bent 50 off end of spring 23 in the make contact and the break contact positions of the armature.

When in the position shown in Fig. 2 the circuit is closed the armature 5 moves in a 55 clockwise sense. It takes the contact nose 18 along with it and bends the hair spring 25 because the end 24 of said spring attached to the arm 19 is kept stationary with said arm by spring 23 while the other fixing 60 point of the spring moves with the contact nose. During this movement the contact nose lifts the contact piece 22 so that the bent-off edge 26 gradually leaves the notch 28 until the contact between 22 and 18 is 65 broken at the moment when edge 26 has reached the edge of tooth 29 the tension of spring 25 will effect the dragging along of the insulating arm and the dropping of spring 23 into the notch 27. The breaking 70 of the contact will deenergize the electro-magnet, so that spring 7 is free to swing 75 the armature 5 back again into the position of Fig. 2.

Due to this swinging of the armature the 75 clockwork is wound up. As soon as armature 5 has taken this position of Fig. 2 pin 20 will come to bear on the arm 19 and push it back until spring 23 has snapped over the tooth 29 and piece 22 has been 80 laid flat upon the nose 18. Then the circuit is closed again and the same play will take place as before.

What I claim is:

In an electric clock a make and break contact device comprising an electro-magnet, an oscillating armature or pallet depending thereon and mounted fast on the driving arbor of the clock, a contact nose and an arm rigidly fast to said armature, and a 85 90

tension or main spring connecting said arm to a stationary stud, a flat contact spring arranged so as to be engaged by said contact nose and having a bent off end, an insulating arm mounted loose on said arbor and provided with notches as rests for the bent off end of the contact spring in its make contact and its break contact positions, a circularly curved hair spring as coupling member between said insulated arm and said contact nose and a carrier pin fast to the contact nose and adapted to disengage said contact spring from the break contact notch.

In testimony whereof I affix my signature.
